UNITED STATES PATENT OFFICE.

BRADFORD L. WILLIAMS, OF CAMDEN, NEW JERSEY.

DESIGN FOR A RUBBER-NEEDLE MASSAGE-BRUSH.

45,441.

Specification for Design.

Patented Mar. 17, 1914.

Application filed November 5, 1913. Serial No. 799,403. Term of patent 3½ years.

To all whom it may concern:

Be it known that I, BRADFORD L. WILLIAMS, a citizen of the United States, residing at the city of Camden, in the county of Camden and State of New Jersey, have invented a certain new, original, and ornamental Design for a Rubber-Needle Massage-Brush, of which the following is a specification, reference being had to the accompanying drawings, forming part hereof, in which—

Figure 1, is a top plan view of the rubber needle massage brush, illustrating my new design; and Fig. 2, is an elevation thereof.

I claim:—

The ornamental design for a rubber needle massage brush, as shown and described.

BRADFORD L. WILLIAMS.

Witnesses:

THOMAS M. SMITH,
HELEN S. HOLT.
